UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SPREADER MECHANISM FOR SEWING-MACHINES.

1,256,271.

Specification of Letters Patent. Patented Feb. 12, 1918.

Application filed December 27, 1915. Serial No. 68,787.

To all whom it may concern:

Be it known that I, DUDLEY S. SEYMOUR, a citizen of the United States, residing at Oak Park, in the county of Cook, State of Illinois, have invented certain new and useful Improvements in Spreader Mechanism for Sewing-Machines, of which the following is a description, reference being had to the accompanying drawing and to the figures of reference marked thereon.

The invention relates to new and useful improvements in overseaming sewing machines, and more particularly to the spreader and the operating mechanism therefor.

An object of the invention is to provide a spreader operating mechanism wherein the end of the spreader when it engages the looper thread below the plane of the work support is moving in a direction substantially vertical and which when reaching the end of its stroke above the work support is moving substantially horizontally, said spreader being operated by devices which are constructed so as to move the spreader through an arc of ninety degrees or more without binding.

A further object of the invention is to provide a spreader operating mechanism by which the spreader will be given an extended dwell at the lower end of its stroke so as to permit the looper to move forward into the needle loop to the end of its stroke and thereby properly position the looper thread for engagement by the spreader.

A still further object of the invention is to provide a spreader operating mechanism wherein the spreader is mounted to swing about a fixed pivot located close to the under face of the work support, and said spreader is operated by toggle links which are moved into alignment for giving a dwell to the spreader when said spreader is at the rear or lower end of its stroke.

These and other objects will in part be obvious and will in part be hereinafter more fully disclosed.

In the drawings, which show by way of illustration one embodiment of the invention:—

Figure 1 is a view, partly in front elevation and partly in section, showing a sewing machine having the improvements embodied therein;

Fig. 2 is a view, partly in plan and partly in section, showing the looper operating mechanism, the spreader operating mechanism, and the feeding mechanism;

Fig. 3 is a view, partly in end elevation and partly in section, with certain of the parts omitted and showing more particularly the manner of mounting the spreader and operating the same;

Fig. 4 is a view on an enlarged scale, partly in front elevation and partly in section, showing the needle, the looper and the spreader, and a portion of the operating mechanisms for the same;

Fig. 5 is a view showing the spreader operating mechanism and the needle with the spreader at the forward end of its stroke;

Fig. 6 is a similar view, but showing the spreader at the rear end of its stroke;

Fig. 7 is a similar view, but showing the spreader partially moved forward;

Fig. 8 is an enlarged detail view showing the relative positions of the needle, the spreader, the looper and the material, the spreader being at the forward end of its stroke;

Fig. 9 is a similar view, but showing the spreader at the rear end of its stroke;

Fig. 10 is a similar view, but showing the spreader moved forward to a point for engaging the looper thread;

Fig. 11 is a similar view, but with the spreader moved farther forward carrying the looper thread around the edge of the material;

Fig. 12 is a plan view of the end of the spreader, showing the looper thread loop held for the needle to enter the same;

Fig. 13 is a view, showing the upper face of the material stitched on the machine;

Fig. 14 is a similar view of the lower face of the material;

Fig. 15 is a front view showing a portion of the material, the needle in section, the spreader, said spreader holding a looper thread loop for the entrance of the needle;

Fig. 16 is a side view of the same, the spreader and the thread finger carried thereby being in section.

The invention is shown as embodied in a sewing machine having a supporting bed 1 carrying a standard 2 having an overhanging arm 3. At the forward end of the over-

- hanging arm is a needle supporting head 4. The needle bar 5 reciprocates in the supporting head and carries a needle 6. Said needle bar is reciprocated by a needle lever 7 pivoted at 8 to the overhanging arm and connected by a link 9 to the needle bar. Said needle lever 7 is oscillated by a link 10 which coöperates with an eccentric on the main shaft 11 of the machine.
- 10 The material to be stitched is carried by a work support 12. A presser foot 13 holds the material on the work support, and a feed dog 14 advances the material over the work support. Said feed dog is carried by a feed bar 15 which is raised and lowered by a suitable cam or eccentric on the main shaft 11, and said feed bar is moved back and forth by an eccentric strap 16 which is connected to the feed rocker 17 at the rear side of the machine, and the feed bar 15 is also pivoted to said feed rocker. These parts are of the usual construction and will not need further description.
- Coöperating with the needle beneath the work support is a thread carrying looper 18. Said thread carrying looper 18 is fixed to a rock shaft 19 mounted in suitable bearings carried by a bracket 20. This rock shaft has an arm 21 with which a link 22 is connected. The link 22 at its other end is connected to a crank arm 23 on a shaft 24. This shaft 24 is mounted in a bearing 25 in the standard 2. At the opposite end of the shaft 24 is an arm 26 which is connected by a link 27 to the needle lever extension 28 on the needle lever 7. The threaded looper is mounted so as to move in a direction toward the standard as it enters the needle loop.
- 40 This looper mechanism forms the subject of a copending application, Serial No. 68,788, filed of even date herewith and is, therefore, only claimed herein in combination with the spreader mechanism.
- 45 Coöperating with the looper 18 is a spreader 29. This spreader 29 has a forked forward end 30 which is adapted to engage the looper thread and also a spaced supporting finger 31 which is secured by a suitable screw 32 to the shank of the spreader, and this finger extends substantially parallel to the lower member of the forked end 30. The spreader 29 is mounted in an arm 33 and is secured therein by suitable screws 34.
- 50 The arm 33 is fixed to the outer end of a short shaft 35. Said shaft 35 is mounted in a bracket 36. The bracket 36 is secured by screws 37 to the bed plate 1. Said bracket is formed with spaced plates 38-38, and these spaced plates form bearings for the shaft 35.
- Connected to the shaft 35 between the supporting bearings therefor is an arm 39. Pivoted to the outer end of the arm 39 is a link 40. This link at its other end is piv-

oted to an arm 41 which is fixed to a short shaft 42. The shaft 42 is also mounted in suitable bearings in the bracket 36. The pivot pin connecting the link 40 and the arm 41 is provided with a ball stud to which is connected a link 43. The link 43 at its other end is connected to a ball stud 44 at the lower end of a lever 45 which is fulcrumed at 46 on the standard 2. The other end of the lever is connected to an eccentric strap 47, 75 which coöperates with an eccentric 48 on the main shaft 11.

In Figs. 13 and 14 of the drawings, is shown a fabric F which is stitched on a sewing machine containing the mechanism above described. The needle thread is indicated at n, while the looper thread is indicated at l. The needle thread passing through the fabric forms a loop into which the looper enters. The looper thread is engaged by the spreader 85 and carried around the edge of the fabric and positioned in loop form for the needle to pass through the same before it enters the fabric. The looper as it enters the needle loop is moving toward the standard of the 90 machine. The spreader is mounted to swing about a fixed pivot which is close to the under face of the work support and near the path of movement of the needle. The supporting arm for the spreader is in the form 95 an elbow which permits this mounting of the spreader at a point close to the under face of the work support, as stated, and at the same time the end of the spreader may be moved to a point above the work support and sufficiently close to the material to permit the needle to enter the looper thread loop carried thereby. The spreader, when at the lower end of its stroke, is disposed only a short distance below the path of movement of the looper. The end of the spreader at this time lies in a horizontal line substantially passing through the pivotal point of the spreader and, therefore, said spreader, 100 when engaging the looper thread, moves in 110 substantially a vertical direction. This moving of the spreader at right angles across the path of movement of the looper insures that the spreader will with certainty engage the looper thread. 115

In order that the spreader may move as above stated, it is necessary for said spreader to move through an arc of at least ninety degrees. The spreader as also noted above, is pivoted close to the work support. By 120 the toggle mechanism shown and described the spreader may be given this long movement without any binding of the operating parts for the spreader. As clearly shown in Fig. 6, the operating arm 39 extends rearwardly of the supporting shaft for the spreader and is substantially horizontal while in Fig. 5 when the spreader is at the upper end of its stroke this arm 39 is substantially vertical. The toggle links 40 and 125 130

41 swing this arm 39 through its long arc movement of ninety degrees or more without any binding action whatever.

The spreader is formed with a forked end 5 which engages and positively holds the looper thread loop for the needle to enter the same. In Fig. 16 of the drawings said spreader is shown at the forward end of its stroke and supporting the looper thread in 10 loop form. Said looper thread is indicated at 7 in this figure. The spreader is also provided with a supporting finger 31. This supporting finger as clearly shown in Fig. 15 of the drawing is directly in rear of the needle when the spreader is at the forward end of its stroke and as the needle comes down into the looper thread loop held by the spreader the needle thread indicated at 8 (see Fig. 16) is laid over the supporting 20 finger 31. The purpose of this supporting finger is to take the slack out of the needle thread and hold the previously interlocked loops in the position to which they have been drawn on the setting of the previous stitch.

25 As will be apparent from Fig. 3 of the drawing, the spreader swings about an axis inclined to the work support and, therefore, the spreader moves in a plane which cuts the work support at an acute angle. This enables the spreader to engage the looper thread loop by a movement in rear of the looper while said spreader moves in front of the needle above the work support. The link 40 and the arm 41 are substantially in 30 alignment when the spreader is at the lower end of its stroke and this construction will, therefore, give to the spreader an extended dwell at the lower end of its stroke. The spreader may, therefore, remain at the lower 35 end of its stroke while the looper is moving into the needle loop and position its thread for engagement by the spreader after the needle has entered the loop formed in the looper thread by the spreader. The spreader 40 then at once releases the looper thread loop.

In Fig. 8 of the drawings, the needle is shown as just about to enter the loop carried by the spreader. In Fig. 9 of the drawings, the spreader is shown as fully retracted 50 and the looper is just about to enter the new needle loop. The spreader must remain in this position until the looper has moved to the forward end of its stroke, as shown in Fig. 10. The toggle link construction above referred to accomplishes this 55 function. After the looper thread loop has been caught by the spreader, then said spreader moves, as shown in Fig. 11, to position the looper thread loop for the entrance 60 of the needle.

It is obvious that minor changes in the 65 details of construction and the arrangement of parts may be made without departing from the spirit of the invention, as set forth in the appended claims.

Having thus described the invention, what is claimed as new is:—

1. A sewing machine including in combination a work support, a needle, means for reciprocating the needle, a thread carrying 70 looper coöperating with said needle beneath the work support, a spreader coöperating with the looper beneath the plane of the work support and with the needle above the work support, a fixed pivotal support 75 for the spreader, and means for oscillating the spreader, said oscillating means including toggle links positioned so as to move into alignment when the spreader is at the rear end of its stroke for giving an extended 80 dwell to the spreader.

2. A sewing machine including in combination a work support, a needle, means for reciprocating the needle, a thread carrying 85 looper coöperating with said needle beneath the work support, a spreader coöperating with the looper beneath the plane of the work support and with the needle above the work support, a fixed pivotal support for the spreader, said pivotal support being 90 located adjacent the under face of the work support and adjacent the path of the needle, and means for oscillating said spreader, said oscillating means including toggle links arranged to move into alignment when the 95 spreader is at the rear end of its stroke for giving an extended dwell to said spreader.

3. A sewing machine including in combination, a work support, a needle, means for reciprocating the needle a thread carrying 100 looper coöperating with said needle beneath the work support, a spreader coöperating with the needle above the work support and with the looper beneath the plane of the work support, a bracket for supporting said 105 spreader said bracket including spaced plates having bearings for the supporting shaft for the spreader, an arm attached to said supporting shaft, a second arm pivoted between said plates, a link connecting said 110 arms and means for oscillating said last named arm for imparting movements to the spreader.

4. A sewing machine including in combination, a work support, a needle, means for 115 reciprocating the needle, a spreader coöperating with the needle above the work support, a supporting shaft for said spreader said shaft being located beneath the work support and adjacent the under face thereof, 120 a bracket for supporting said spreader, said bracket including spaced plates having bearings for the supporting shaft for the spreader, an arm fixed to said shaft, a second arm pivoted to said supporting plates 125 and directly beneath the supporting shaft for the spreader, a link connecting said arms and means for oscillating the last named arm for imparting movements to the spreader.

5. A sewing machine including in combination, a work support, a needle, means for reciprocating the needle, a spreader, cooperating with the needle above the work support, a supporting shaft for said spreader said shaft being located beneath the work support and adjacent the under face thereof, a bracket for supporting said spreader, said bracket including spaced plates having 5 bearings for the supporting shaft for the spreader, an arm fixed to said shaft, a second arm pivoted to said supporting plates 10

and directly beneath the supporting shaft for the spreader, a link connecting said arms, an operating member attached to the pivotal connection between the last named arm and the link for oscillating the arm and imparting movements to the spreader.

In testimony whereof, I affix my signature, in the presence of two witnesses.

DUDLEY S. SEYMOUR.
